UNITED STATES PATENT OFFICE.

WILLIAM HENRY MERITON SIEGEL, OF STADE, NEAR HAMBURG, GERMANY.

SOUNDING BOARD FOR PIANOS.

Application filed July 5, 1924, Serial No. 724,329, and in Germany May 3, 1924.

Object of the invention is to improve the tone of the instrument with regard to firmness and length of sound, which object will be obtained by firmly attaching to the usual 5 wooden ribs being provided on the rear face of the wooden sound board struts in such a manner that they adhere with a flat face to the sound board just in the rear of the usual bridge and with a straight edge to the adjacent rib. The attaching of said sound board to the adjacent parts is effected by gluing or by means of pins, wood-screws or by both 10 agencies or the like.

The struts can be carried out in such a 15 manner that they are of curved, segmental, or angular contour or completely fill the spaces between each two adjacent ribs just in the rear of the ribs.

The improvement of the tone is created 20 by the fact that the ribs are securely fixed at the section point where they are crossing the bridges in such a way that the stiffening is transposed upon the middle field between the ribs.

25 It has been proposed already to employ stiffening ribs on the sound boards said ribs being connected by transverse ribs, but these latter were only for the purpose of stiffening and straining the first said ribs. It has 30 also been proposed to use struts between the usual ribs but these struts have been attached only to the sound board with their bottom face without touching said ribs.

35 In the accompanying drawings forming a part of this specification and showing, for purposes of exemplification, a preferred form and manner in which my invention may be embodied and practised, but without limiting the claimed invention to such illustrative instance:

40 Figure 1 is a sectional view of a piano showing diagrammatically the location of the sound-board therein; Figure 2 is a rear view of the sound-board constructed in accordance with my invention; Figure 3 is a section on the line III—III of Figure 2; Figure 4 represents a partial section on the line IV—IV of Figure 3; Figure 5 is a view 45 similar to Figure 2 showing a modified embodiment of my invention; Figure 6 illustrates a section on the line VI—VI of Figure 5; Figure 7 represents a partial section on the line VII—VII of Figure 6 and Figure 8 is a fragmentary illustration of the 50 sound-board showing struts of a modified form.

Parts that are repeated in the several figures bear the same reference characters in each case.

55 In the drawings *a* is the wooden sound-board which, as hereinbefore stated, is shown diagrammatically in Figure 1 so that the construction and arrangement of the struts cannot be seen which, however, are clearly depicted in the other figures. *b* is the usual bridge on the front side of the sound-board and supplemental bridges such as *b'* may be provided if desired. The bridges are attached to the sound-board by 60 gluing or by means of pins, wood-screws or by both agencies. The ribs or strips *c* made of wood are of conventional shape and arranged in parallelism transversely over the rear face of the sound-board so as to cross the direction of the stay or bridges provided 65 on the opposite or front face of the board.

70 The struts *d* are flat pieces of wood of segmental shape as in Figure 2 or of triangular shape as in Figure 8, and they are firmly attached with a flat, plane face to the sound-board and with a straight edge to the adjacent rib just in the rear of the usual bridge. In some cases, however, I prefer to 75 employ wooden bodies of any suitable contour, such as *d'* shown in Figure 5 by way 80 of example, which fill completely the spaces between each two adjacent ribs.

85 It is not necessary to give all of the struts the same shape, contour or size. The size of the bodies may gradually decrease in conformity with the diminishing length of the ribs as will be seen in Figure 2 or bodies of 90 different shape may be employed on one and the same sound-board, as shown in Figure 5.

95 By the use of the limitation "struts" in the specification and claims it is not intended to imply that such struts are merely strengthening members, but as applied to the structure they have a musical value in 100 that they produce a resonant effect.

105 What I claim is:

110 1. A sound board for use in pianos comprising a wooden board, wooden ribs on one face of said board, and struts having a flat face firmly attached to the sound board just in the rear of the usual bridge, said struts having a straight flat side edge firmly attached to a wooden rib.

2. A sound board for use in pianos comprising a wooden board, wooden ribs on the rear face of said board, bridges secured to

the opposite face of the board, struts of segmental angular contour firmly attached with the flat face to the sound board just in the rear of a bridge, and having a straight flat edge firmly secured to an adjacent rib.

3. A sound board for use in pianos comprising a wooden board, wooden ribs on the rear face of said board, a bridge secured to the opposite face of said board, struts having a flat face firmly attached just in the rear of the bridge and having a straight flat edge, and means for firmly securing the flat edge of the struts to an edge of a rib.

4. A sound board for use in pianos comprising a wooden board, wooden ribs on the rear face of said board, bridges secured to the front face of said board, struts, means for firmly attaching the struts having a flat face, means for securing the flat face of a strut to the sound board just in the rear of a bridge, said struts each having a flat side secured to an edge of a rib, each strut being located upon opposite edges of the rib and completely filling the space between each pair of adjacent ribs.

WILLIAM HENRY MERITON SIEGEL.
